(57) **CLAIM**

The ornamental design for a tire, as shown and described.

DESCRIPTION

FIG. 1 is a perspective view of the tire showing my new design;

FIG. 2 is a front view thereof;

FIG. 3 is a side view thereof;

FIG. 4 is a perspective view of another embodiment of my design;

FIG. 5 is a front view thereof; and,

FIG. 6 is a side view thereof.

The portions shown in broken lines form no part of the claimed design.

1 Claim, 6 Drawing Sheets
